(57) **CLAIM**

The ornamental design for an ceiling-mounted air conditioner, as shown and described.

DESCRIPTION

FIG. 1 is a front perspective view of a ceiling-mounted air conditioner showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a front perspective view thereof showing the ceiling-mounted air conditioner in an alternate configuration;

FIG. 9 is a front view thereof;

FIG. 10 is a rear view thereof;

FIG. 11 is a left-side view thereof;

FIG. 12 is a right-side view thereof;

FIG. 13 is a top view thereof;

FIG. 14 is a bottom view thereof;

FIG. 15 is an enlarged view of the encircled portion in FIG. 9; and,

FIG. 16 is an enlarged view of the encircled portion in FIG. 8.

The evenly-dashed broken lines in the figures depict portions of the ceiling-mounted air conditioner which form no part of the claimed design.

The dot-dot-dash broken lines encircling portions of the claimed design that are illustrated in enlargements form no part of the claimed design.
